(57) **CLAIM**

The ornamental design for an injector, as shown and described.

DESCRIPTION

FIG. 1 is a perspective view of an injector showing our new design;

FIG. 2 is a left side view thereof, the right side view being a mirror image;

FIG. 3 is a left side view thereof in an alternate position, the right side view being a mirror image;

FIG. 4 is a left side view thereof in an alternate position, the right side view being a mirror image; and,

FIG. 5 is a left side view thereof in an alternate position, the right side view being a mirror image.

1 Claim, 5 Drawing Sheets

FIG. 1

FIG. 2

FIG. 3

FIG. 4

FIG. 5
